UNITED STATES PATENT OFFICE

EMIL T. SIESKO, OF NANTICOKE, PENNSYLVANIA

REAMER FOR PIPE THREADERS

Application filed March 16, 1927. Serial No. 175,789.

This invention provides means whereby a pipe may be threaded and the burr removed at one operation and without necessitating readjustment or the stopping of the cutting action of the threading tool, both operations being effected on the forward movement of the tool.

The invention supplies a reamer which is adapted to be readily attached to a pipe 10 threading tool and adjusted to the size of the pipe to be threaded without interfering in the least with the ordinary operation or use of the tool.

The invention furthermore provides a 15 reamer attachment of the character aforesaid which may be marketed at relatively small cost and which is adjustable to be easily adapted to pipe threading tools of different sizes within certain limits.

20 While the drawings illustrate a preferred embodiment of the invention it is to be understood that in adapting the means to meet specific needs and requirements the design may be varied and such other changes 25 in the minor details of construction may be resorted to within the scope of the invention as claimed, without departing from the spirit thereof.

For a full understanding of the invention 30 and the merits thereof, reference is to be had to the following description and the drawings hereto attached, in which,

Figure 1 is a detail sectional view of a 35 reamer attachment showing it in operative relation.

Figure 2 is a detail perspective view of the attachment, the parts being separated and disposed in a group.

40 Corresponding and like parts are referred to in the following description and designated in the several views of the drawings by like reference characters.

The die stock illustrated is of well known construction and has been selected to demonstrate the application of the invention. The frame or head of the die stock is designated by the numeral 1 and 2 indicates the usual handles removably fitted thereto.

45 The reamer attachment comprises a frame including a yoke which comprises spaced

side pieces 3 and a connecting end piece 4 in which is formed an opening 5 to provide clearance for the stem 6 of the reamer 7. The side pieces 3 have longitudinal slots 8 formed therein to receive the reduced ends 55 of a cross head 9, in which is formed an opening 10 of noncircular outline to receive the stem of the reamer to cause the latter to rotate with the thread forming tool. Threaded stems 11 project outwardly from the reduced ends of the cross head 9, and receive clamp nuts 12 by means of which the cross head is made secure in the required adjusted position.

50 Lugs 13 project outwardly in opposite directions from the free ends of the side pieces 3 and provide convenient means for attaching the reamer to the head or frame of the die stock. Similarly formed connectors 14 are adjustably coupled at one end to each of the lugs 13 and the opposite end is formed with an opening 15 through which a handle 2 extends, whereby to secure the reamer to the threading tool. Opposite end portions of the connectors 14 are disposed at a right 55 angle to one another, and the end in contact with the lug 13 is formed with a threaded opening 16 to receive a screw 17 provided to secure the yoke to the connectors. Each of the lugs 13 is formed with an elongated 60 opening 18 to receive the screw 17 and admits of adjustment of the connectors 14 whereby the attachment may be readily adapted to different die stocks. The end portions of the connectors 14 which engage 65 the lugs 13 are provided at one side with a flange 19 which is adapted to sustain the thrust when the reamer is in operation, and thereby relieve the bolts 17 of the major 70 part of the strain.

75 These connectors are provided with an inwardly projecting shoulder intermediate their end portions, constituting an abutment or bearing for the upper surface of the frame or head of the die stock 1, to give increased rigidity to the assembled combination of die stock, reamer frame and connector.

80 One of the connectors is provided inter- 100

mediate the angularly disposed ends with an observation opening 22 through which the usual indications on the face of the die stock may be read.

5 The cross head 9 is adjustable between the side pieces 3 of the yoke and is made fast in the required adjusted position by means of the clamp nuts 12 between which and the shoulders at the base of the reduced ends of 10 the cross head the side pieces 3 are clamped. Scale graduations 23 are provided along an edge of one of the side pieces 3 and in conjunction with an indicating mark on the cross head 9 enables the latter and the 15 reamer to be properly adjusted according to the size of the pipe to be screw threaded. The stem of the reamer is usually tapered and of square formation and the opening 10 formed in the cross head 9 is of corresponding shape to snugly receive said stem and 20 hold the reamer 7 in place. When the attachment is applied to a pipe threading tool it is rotated with the tool when threading a pipe. The reamer is adjusted so that during 25 the final cutting of the thread the reamer is brought into action to remove the burr from the end of the pipe formed by the usual pipe cutting tool. Both operations are performed simultaneously and during the advance of the threading tool, thereby obviating 30 the stopping of the tool or necessitating the readjustment thereof.

Having thus described the invention, I claim:

35 1. A reamer attachment for pipe threading tools, the same comprising a frame including a yoke having outwardly disposed lugs providing means of attachment to the threading tool, the side pieces of the yoke 40 being formed with longitudinal slots, a cross head adapted to receive and carry the reamer and formed with reduced end portions disposed to operate in the longitudinal slots of the side pieces, and having threaded 45 stems projecting outwardly from the reduced ends, and clamp nuts mounted upon said threaded stems to secure the cross head to the yoke in the required adjusted position, there being an indicating mark on the 50 cross head and coacting scale graduations on a side piece of the yoke, to admit of proper adjustment of the reamer.

55 2. A reamer attachment for pipe threading tools, the same comprising a frame including a yoke having its side pieces longitudinally slotted and provided at their ends with outwardly disposed lugs in which are formed elongated openings, a cross head having reduced ends disposed in the slotted 60 side pieces of the yoke, means for securing the cross heads in the required adjusted positions, connectors having opposite end portions disposed relatively at a right angle, one of the ends being apertured to receive 65 the handles of the threading tool, and means

adjustably connecting the other end to a lug of the yoke.

3. In combination with a pipe threading diestock having handles and a reamer attachment therefor having a yoke provided with outwardly disposed lugs, means for connecting the attachment to the diestock comprising a pair of relatively flat members each having perforated end portions disposed at approximately right angles to each other, one of said perforations being adapted to receive one of said handles, means passing through the other of said perforations to couple the connector to one of said lugs, and an inwardly projecting shoulder intermediate the end portions adapted to abut against a portion of the diestock.

In testimony whereof I affix my signature.

EMIL T. SIESKO. [L.S.]
